UNITED STATES PATENT OFFICE.

MAX RÜPING, OF MUNICH, GERMANY, ASSIGNEE TO DÜBELWERKE G. M. B. H., OF BERLIN, GERMANY.

REINFORCED RAILROAD CROSSTIE.

Application filed December 8, 1925. Serial No. 74,093.

To all whom it may concern:

Be it known that I, MAX RÜPING, a citizen of the Republic of Germany, residing at 172 Ismanningerstrasse, Munich, Germany, have 5 invented certain new and useful Improvements in Reinforced Railroad Crossties, of which the following is a specification.

This invention has reference to means of increasing the duration of railroad cross-ties 10 by providing the wooden cross-ties at the points where the rails are supported with a lining plate of hard wood arranged with its fibers to run in the direction of the fibers of the cross-ties or sleepers. It has been usual 15 to employ such lining plates or blocks as a means of rendering cross-ties available for use which have become unfit for use by the widening of the spike holes, the surface of the cross-tie being indented to a certain 20 depth and for a certain length, and the indentation being then filled with one or more lining plates or blocks.

However, the lining means of the kind referred to and suggested by the previous 25 art have not been very satisfactory and did not fully come up to the requirements of railroad operation. The wooden lining plates heretofore used were either arranged with their fibres transversely with relation 30 to the tie, in which case the plates, though protected from splitting, were loosened in the indentation as a result of changes of temperature, so that they required tightening; or, on the other hand lining plates or blocks 35 were used with their fibers in the longitudinal direction of the tie. With this arrangement there was the difficulty, however, that the plates were torn and broke open by the action of the weather and of the pressure of 40 the rails. It has also been suggested to make the indentation in the cross-tie of circular shape, in order to avoid tearing of the lining plate. Though with this arrangement the initial tearing and breaking open of the lining 45 plate could be avoided, the pointed angular pieces on the surface of the tie at the side of the indentation were forced away and broken off, and after the removal of these angles the lining plate itself had, of 50 course, to give away and burst. These difficulties and inconveniences are overcome in this invention by providing strips of sheet metal with lateral ears, such strips being forced into the transverse joints between the 55 edges of the indentations of the ties and the

edges of the lining plates or blocks disposed in the indentations with their fibers in the longitudinal direction of the ties. The ears of these strips are thereby forced both into the tie as well as into the lining plate with 60 the result that the lining plate is thereby secured in a simple and unobjectionable manner both against bursting and tearing, as well as against displacement.

The invention will be more particularly 65 described with reference to the accompanying drawing showing by way of exemplification a preferred form of embodiment of the principles of the invention, Figure 1 being a longitudinal section through the portion of the tie provided with the lining plate. Figure 2 is a top plan view according to Figure 1, and Figure 3 is a plan view of the metal strip employed for retaining the lining plate in position and for securing the same against 70 bursting and tearing. Figure 4 is a side view of the metal strip. Figure 5 shows the original shape of the metal strip before the bending of the ears. In the cross-tie *a* the depression or indentation *b* is cut out in 75 which the lining plate or block *c* is lodged in such a manner that its fibers are running in the same direction with those of the cross-tie. The lining plate *c* itself is provided with an indentation *d* in which the foot of the rail is disposed. In order to prevent bursting and tearing of this lining plate *c* under the action of the weather and of the operating strains and in order to retain it 80 against displacement in the indentation the sheet iron strips *f* are forced into the transverse joints at the end faces of the lining plate, each joint being provided with a metal strip. These sheet iron strips are shown 85 particularly in Figures 3 to 5 of the drawing. The manufacture of these fastening and securing strips is substantially effected 90 as follows:

In the sheet metal strip *f* the cross cuts *g* and the longitudinal cuts *h* are provided, as 100 appears from Figure 5 of the drawing. The sectional portions *i*₁, *i*₂ thereby obtained are bent alternately towards the front and rear sides of the strip; and the ends of the strip *f* are likewise bent respectively forward and rearward, and by this means the strip *f* is given the shape shown in Figures 105 3 and 4 of the drawing.

The block or lining plate *c*, shown in Figures 1 and 2 is provided at its end faces, and 110

particularly at the edges thereof, with incisions or notches at right angle to the end faces and to the upper surface thereof and spaced from each other to correspond to the ears of the strips *f*. Then said strips *f* are forced by hammer blows or the like into the transverse joints between the tie and the lining plate *c* and in such a manner that the ears *i*₁, *i*₂ are made to engage respectively with the tie and the block or lining plate *c* the ears *i*₂ engaging with the incisions or saw-cuts in the lining plate, and the ears *i*₁ engaging with the transverse surface of the cross-tie itself adjacent the sheet metal strip *f*. The length of the strips *f* corresponds to the breadth of the cross-tie, so that the bent ends of the strips are caused to bear upon the longitudinal faces of the tie and of the lining plate respectively.

20 By means of the ears the lining plate becomes subdivided into comparatively small subdivisions or sections, so that upon the drying-up and contracting of the lining plate *c* this contraction cannot result in the formation of broad or transverse fissures, but will at most result in the formation of small innocuous capillary fissures. There is no further contraction of a lining plate mounted according to this invention in the longitudinal direction of the tie, so that the said block or lining plate *c* will always snugly and completely fill the indentation, while at the same time displacement in the transverse direction is reliably prevented by the sheet metal strips *f*, as hereinbefore set forth.

While the invention has been described and shown with reference to a preferred exemplification thereof it is to be understood that it is not limited to this particular con-

struction and arrangement of parts, but that it is susceptible of modifications and changes within the scope and spirit of the invention, as defined by the appended claims.

I claim:—

45 1. A reenforced railroad cross-tie, including in combination with a topwise recess and a lining plate in the recess of said tie with its fibers running substantially in the same direction as the fibers of the tie, and sheet metal strips disposed between the adjacent faces of the tie and of the lining plate, of lateral projections on said strips engageable with the tie and the lining plate.

50 2. In a reenforced railroad cross-tie having in combination, a topwise recess, a wooden lining plate in the recess of said tie with its fibers running substantially in the direction of the fibers of the tie, sheet metal strips between the adjoining faces of the tie and of the lining plate, and spacedly and angularly disposed lateral ears on said strips engageable with the tie and with the lining plate and with the outer surface thereof.

55 3. In a reenforced railroad cross-tie having in combination, a topwise recess, a wooden lining block lodged in the recess of said tie with its fibers running substantially in the direction of the fibers of the tie, sheet metal strips transversely disposed between the adjoining faces of the tie and of the lining block, alternatingly oppositely directed, spacedly disposed lateral ears on said strips respectively engageable with the tie and with the lining block, and oppositely directed ears at the ends of said strips respectively engaging the outer surfaces of the tie and of the lining block.

60 In testimony whereof I affix my signature.

MAX RÜPING.
